Primary Examiner — Ramzi S Almatrahi*(74) Attorney, Agent, or Firm* — Jones Robb, PLLC(57) **CLAIM**

The ornamental design for a handheld imaging device, as shown and described.

DESCRIPTION

FIG. 1 is a top, front and right side perspective view of a handheld imaging device showing our new design;

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines depict portions of the handheld imaging device in which the design is embodied that form no part of the claimed design.

1 Claim, 5 Drawing Sheets(56)
